UNITED STATES PATENT OFFICE.

JOSEPH LEWIS POTTER AND JOSEPH LE ROY POTTER, OF INDIANAPOLIS, INDIANA.

EXCAVATING APPARATUS.

1,360,681.

Specification of Letters Patent. Patented Nov. 30, 1920.

Application filed December 24, 1917. Serial No. 208,682.

To all whom it may concern:

Be it known that we, JOSEPH LEWIS POTTER and JOSEPH LE ROY POTTER, citizens of the United States, residing at Indianapolis, 5 in the county of Marion and State of Indiana, have invented a new and useful Improvement in Excavating Apparatus, of which the following is a specification, reference being had to the accompanying drawings, and to the letters and figures of reference marked thereon.

This invention relates to the type of excavating apparatus which is adapted for slack-line work with a scoop or drag bucket, 15 the invention having reference more particularly to means for mounting the bucket on a controllable cable or slack-line for movably supporting the bucket and permitting it to be controlled so as to quickly dump its 20 load; the invention having reference also to means for operating and generally controlling the bucket in operation.

An object of the invention is to provide simple and inexpensive means for accomplishing excavating operations by the slack-line method in a convenient, expeditious and economical manner.

Another object is to provide improved excavating apparatus which shall be especially 30 adapted to be efficiently used and operated by the minimum number of operators or attendants, whereby a high degree of economy in operation may be attained.

A further object is to provide improved 35 drag bucket construction and improved means for supporting and controlling the operations of the bucket without requiring troublesome structural features such as drop bottoms, latching devices, springs or other 40 elements that are liable to become damaged or deranged due to rough usage with consequent expense for repairs.

With the above-mentioned and other objects in view, the invention consists in an 45 improved dumping bucket or scoop having improved supporting and controlling apparatus whereby to operate the bucket and automatically control the bucket so that it shall be tilted forward to dump its load and again righted to receive another load. 50 The invention consists also further in the novel parts and in the combinations and arrangements of parts or elements as herein-

after particularly described and further set forth in the accompanying claims. 55

Referring to the drawings:—Figure 1 is a side elevation of the improved excavating apparatus in working position for trench work, a hoisting machine of well-known construction being indicated by broken lines 60 as being adapted for use in connection with the invention; Fig. 2 is a side elevation of the principal features of the invention in which the bucket is shown as when being carried with a load to be dumped, the carriage of the apparatus being in vertical section; Fig. 3 is an end elevation of the carriage comprised in the invention; Fig. 4 is a section on the line IV—IV on Fig. 2; and, Fig. 5 is a side elevation, partially in section, 65 of the principal elements of the invention, the bucket being shown in the position required for dumping the load. 70

Corresponding reference characters on the different figures of the drawings indicate 75 like elements or features of construction herein referred to.

On the drawings the numeral 1 indicates a section of the earth in which a trench 2 is partially made, and ahead of the trench is a 80 car 3 that has an upright frame 4 and also winding drums 5 and 6 so as to constitute a hoisting machine. Opposite to the car and beyond the trench is a suitable post or anchor block 7 to which a slack-line or aerial 85 cable 8 is connected and slackened or tightened by means of tackle blocks 9 and 10, and a cable 11 which is connected with the winding drum 5. The frame supports a sheave 12 on which the cable 11 is guided and it 90 supports also a guide sheave 13 below the sheave 12. The tackle block 10 is arranged sufficiently high to support the adjacent end of the cable 8 at a higher altitude than the opposite end of the cable, so that the cable 95 is inclined and may be slackened according to common practice.

An improved carriage is provided which 100 comprises two side members 14 and 15 suitably connected together with space between them and provided with carrying wheels 16 and 17 between the members, the wheels being arranged to run upon the cable 8. The carriage is provided between the side members with a supporting sheave 18 and a guide 105 sheave 19 and also lugs 20 and 21.

The improved drag bucket or scoop comprises a body portion 22 having a bottom 23 and a forward extension 24, the forward end of the bottom being provided with digging teeth 25. The extension of the body portion is provided with a sheave 26 which preferably is arranged on an arch or top 27 forming a portion of the bucket. The top 27 has also a rigid longitudinal rib 28 thereon having a plurality of apertures 29 therein. A cable 30 is hung on the lug 20 and extends under the sheave 26, thence over the sheave 18 and thence to the rib 28 and adjustably connected thereto by means of one 15 of the apertures 29, so as to tiltably support the bucket on the sheave 18. A drag-line or draft cable 31 is connected with the winding drum 6 and extends over the sheave 13 and thence below the cable 8 and it has a 20 yoke portion 32 connected with the forward portion of the bucket, and also a branch 33 connected to the lug 21. The bucket has a back or rear end 34 which is provided with an arm or bail 35. The latter preferably being 25 designed to constitute a link is connected by means of a pivot 36 with ears 27 projecting from the rear end of the bucket bottom 23. A controlling cable 38 is connected to the end of the arm or bail and extends 30 over the guide sheave 19 for controlling the tilting of the bucket. The cable 38 preferably is controlled by means of a yoke which comprises two side members 39 and 40 secured to spacing blocks 41 and 42 and provided 35 with a lug 43, the opening between the side members receiving the cable 8 which supports the spacing block 41. The yoke is adapted to be held against the rear end of the carriage by the cable 38 which is connected to the lug 43. A stop block 44 is secured to the cable 8 and is adapted to prevent the yoke from being drawn over it but is sufficiently small to be received in the space provided in the carriage and permit 40 the carriage wheels to roll over it.

In practical use the carriage rolls by the force of gravity down the inclined cable 8 and carries the bucket to the desired position for excavating, after which the cable 50 8 is slackened so as to lower the bucket as may be required, the yoke on the cable 8 being pushed along by the carriage as the latter descends. Upon properly operating the winding drum 6 the bucket is drawn forward until filled, after which the winding drum 5 is properly operated to draw up the cable 8 as may be required to hoist the bucket from the trench. The bucket on being hoisted and carried by the carriage is 55 caused by the load therein to tilt as indicated in Fig. 2 so as to retain the load. The draft yoke 32 being slackened permits the branch 33 to draw the carriage forward and over the stop block 44, the cable 38 being held taut by the bucket and drawing the 60 65

yoke members 39 and 40 against the carriage until the yoke is brought into contact with the block 44 and stopped while the carriage is drawn farther forward, the action causing the cable 38 to be drawn up 70 over the guide sheave 19 and thus force the rear end of the bucket upward, resulting in the bucket being tilted over relatively to the sheave 18 and the arm 35 with the forward end of the bucket downward so that 75 the load must be discharged from the bucket. On permitting the cable 31 to be unwound from the winding drum 6, the carriage again descends until it engages the yoke on the cable 8 and carries the yoke downward 80 as before, the cable 38 being thus permitted to run down over the sheave 19 so that the bucket again becomes righted as it is lowered into the trench to repeat the excavating operation. The whole proceeding, as 85 will be seen, is automatic upon operation and control of the winding drums 5 and 6.

Having thus described the invention, what is claimed as new is—

1. An excavating apparatus including an aerial cable, hoisting means for slackening or tightening the cable, a block secured to the cable, a carriage adapted to receive the block and having wheels mounted on the cable to roll over the block, the carriage being provided with a guide sheave, a yoke movably supported on one cable on the side of the carriage to be moved thereby away from the hoisting means, a drag bucket 90 tiltingly supported by the carriage and provided with a controlling cable extending over the guide sheave and secured to the yoke to hold the yoke to the carriage or permit the block to stop the yoke when the carriage receives and passes the block, and a drag-line connected with the bucket and having a branch connected to the carriage. 95 100 105

2. In an excavating apparatus, the combination with an inclined cable, and a stop block secured to the cable, of a carriage 110 movably mounted on the cable and adapted to receive and pass over the stop block, the carriage being provided with a guide sheave, a yoke movably mounted on the cable and arranged to be engaged and pushed by the carriage down the cable, the yoke being adapted to be stopped by the block on movement of the carriage and the yoke upward on the cable, a bucket tiltingly hung on the carriage, a drag-line having 115 connection with the bucket and the carriage, and a cable operatively connected with the bucket and the yoke and extending over the guide sheave. 120

3. In an excavating apparatus, the combination with a carriage having a supporting sheave and a guide sheave, of a drag bucket comprising a body with a top and a bottom and also a rear end, the top of the bucket body having a rib longitudinally ar- 125 130

ranged thereon, the rib having a plurality of apertures therein, an arm pivotally connected with the rear end of said body adjacent to said bottom, a supporting cable connected with said rib in one of said apertures and extending over the supporting sheave to and coöperating with the forward portion of said body top to tiltingly support the bucket, and a cable secured to the arm and

extending over the guide sheave to control 10 the tilting movement of the bucket.

In testimony whereof, we affix our signatures in presence of two witnesses.
